(57) **CLAIM**

The ornamental design for a radial heat conductor, as shown and described.

DESCRIPTION

U.S. application Ser. No. 14/058,230 filed Oct. 19, 2013 titled “Maximizing the Lighting Efficiency of LED Lamps”.

FIG. 1 is a top plan view of a radial heat conductor, showing our new design.

FIG. 2 is an top perspective view of a radial heat conductor; and,

FIG. 3 is a side elevation view of a radial heat conductor.

1 Claim, 3 Drawing Sheets

FIG. 1

FIG. 2

FIG. 3
